(57) **CLAIM**

The ornamental design for a luminaire with a continuous lens, as shown and described.

DESCRIPTION

FIG. 1 is a bottom perspective view of a luminaire with a continuous lens, showing our new design;

FIG. 2 is a top perspective view thereof;

FIG. 3 is a top plan view thereof;

FIG. 4 is a bottom plan view thereof;

FIG. 5 is a left side view thereof;

FIG. 6 is a right side view thereof;

FIG. 7 is a front view thereof; and,

FIG. 8 is a rear view thereof.

The broken lines shown in the figures represent portions of the luminaire with a continuous lens that form no part of the claimed design.

The area between the dash-dot-dash lines in the figures forms no part of the claimed design for a luminaire with a continuous lens.
